Boston Type Foundry, No. 104 Milk Street, Boston.

UNITED STATES PATENT OFFICE

JOHN K. ROGERS, OF BROOKLINE, MASSACHUSETTS.

DESIGN FOR PRINTING-TYPE.

SPECIFICATION forming part of Design No. 12,869, dated April 11, 1882.

Application filed April 28, 1881. Term of patent 3½ years.

To all whom it may concern:

Be it known that I, JOHN K. ROGERS, a citizen of the United States, residing at Brookline, in the county of Norfolk and State of Massachusetts, have invented and produced a new and original Design for a Font of Printing-Types, of which the following is a specification, reference being had to the accompanying impression, taken from said font.

My design consists of an alphabet or font of capital letters, with figures, points, and center piece, as shown.

The general character of the alphabet may be described as a skeleton or light-line Roman letter, with novel effects, among which the most marked are the K, in which the lower diagonal line crosses the upper and terminates in a curved swell, and the W, in which the center lines cross each other and terminate in a similar manner. Further novel effects are shown in the cross-lines of the A and H, which are drawn down to a point in the center, and

are extended beyond the upright lines at each side; in the B, P, and R, when the usual cross-lines are carried upward with a curve to the right; in the M and N, which are shaped like the ordinary Roman lower-case m and n, but are extended below the line on the right-hand side, terminating in a curve; in the symbol & and numerals 3 and 8, which are formed with horizontal lines at the top; in the center piece, which has a horizontal row of dots and three radiant lines at top and bottom; one end piece with five radiants, two being dots, the other end piece triangular, with a curved extension at the side.

I claim—

The design for a font or alphabet of printing-types, as described and shown.

JOHN K. ROGERS.
